US0D1037266S

(12) **United States Design Patent** (10) **Patent No.:** **US D1,037,266 S**
(45) **Date of Patent:** **** Jul. 30, 2024**

(54) **DISPLAY SCREEN WITH GRAPHICAL USER INTERFACE**

(71) Applicant: **HUAWEI TECHNOLOGIES CO., LTD.**, Shenzhen (CN)

(72) Inventors: **Qing Zhuang**, Shenzhen (CN); **Shu Xie**, Shenzhen (CN); **Peng Ge**, Shenzhen (CN)

(73) Assignee: **HUAWEI TECHNOLOGIES CO., LTD.**, Shenzhen (CN)

(**) Term: **15 Years**

(21) Appl. No.: **29/753,046**

(22) Filed: **Sep. 29, 2020**

(30) **Foreign Application Priority Data**

Apr. 1, 2020 (CN) 202030121837.8

(51) **LOC (14) Cl.** **14-04**

(52) **U.S. Cl.**

USPC **D14/486**; D14/487

(58) **Field of Classification Search**

USPC D14/485-495

CPC G06F 3/048-04897

See application file for complete search history.

(57) **CLAIM**

The ornamental design for a display screen with graphical user interface, as shown and described.

DESCRIPTION

FIG. 1 is a front view of a first embodiment of a display screen with graphical user interface, showing our new design;

FIG. 2 is a front view of a second embodiment of a display screen with graphical user interface, showing our new design;

FIG. 3 is a front view of a third embodiment of a display screen with graphical user interface, showing our new design; and,

FIG. 4 is a front view of a fourth embodiment of a display screen with graphical user interface, showing our new design.

The broken line in each figure illustrates a display screen that forms no part of the claimed design.

1 Claim, 4 Drawing Sheets
